DISHWASHER CABINET OR THE LIKE

Elmer H. Daniels, Pasadena, Calif., assignor to
Kaiser Fleetwings, Inc., Oakland, Calif., a corporation of California

Application September 19, 1947, Serial No. 141,492

Term of patent 3½ years

(Cl. D49—1)

To all whom it may concern:

Be it known that I, Elmer H. Daniels, residing at Pasadena, in the county of Los Angeles and State of California, have invented a new, original, and ornamental Design for a Dishwasher Cabinet or the like, of which the following is a specification, reference being had to the accompanying drawing, forming part thereof.

The figure is a perspective view of a dishwasher cabinet or the like, showing my new design. The other side of the said cabinet is substantially like the side shown.

I claim:

The ornamental design for a dishwasher cabinet or the like, substantially as shown and described.

ELMER H. DANIELS.
